UNITED STATES PATENT OFFICE.

ALFRED HENRY DARKER, OF BLACKHEATH, ENGLAND, ASSIGNOR TO J. STONE & COMPANY, LIMITED, OF DEPTFORD, ENGLAND.

METHOD OF AND APPARATUS FOR ELECTRICAL DISTRIBUTION.

1,279,283.

Specification of Letters Patent. Patented Sept. 17, 1918.

Original application filed March 18, 1910, Serial No. 550,136. Divided and this application filed May 15, 1918. Serial No. 97,654.

To all whom it may concern:

Be it known that I, ALFRED HENRY DARKER, a subject of the King of Great Britain, and residing at Heathview, Montpelier Row, Blackheath, in the county of Kent, England, have invented certain new and useful Improvements in Methods of and Apparatus for Electrical Distribution, of which the following is a specification.

10 This invention relates to a method of and apparatus for electrical distribution and has particular reference to electrical car lighting and heating systems wherein the generator is driven from the axle of a railroad car or the shaft of an automobile or other vehicle to which the system is applied; and although useful in other systems, it is of particular value in connection with car lighting systems in which the generating

20 dynamo is of the constant torque type. This invention is a division of my application Ser. No. 550,136, filed March 18, 1910.

One of the primary objects of my invention is the provision of an improved method 25 of electrical distribution in lighting and heating systems having a battery to be charged, by means of which I eliminate the complicated automatic regulating means which must be employed, for example, in 30 electrical lighting systems of the constant current type in which the voltage of the dynamo must be automatically regulated by such means, or of the constant voltage type in which the current must be regulated by 35 similar means.

My invention further contemplates the provision of an improved method of electrical distribution in a system of the character described which is simple in character 40 and is adaptable to varying service conditions, such, for example, as where a car is used on a short run on one day and on a long run the next.

Another object of my invention is the provision of an improved method of and apparatus for automatically changing the cut-in speed at which the dynamo will deliver a useful current upon certain changes in the state of the battery charge.

50 A still further object of my invention is the provision of an improved method of

changing the moment of belt slippage in a lighting system employing a slipping belt type of dynamo.

I also provide improved apparatus for 55 accomplishing the foregoing and for securing certain advantageous results which will be more fully hereinafter set forth.

The foregoing, together with such other objects as may hereinafter appear or are incident to my invention I attain by means of a method and apparatus diagrammatically indicated in the accompanying drawings in which only such parts of the system as are necessary to effect an understanding of my 65 invention are illustrated, it being understood that the invention is not limited to the precise arrangement and means shown.

Referring to the diagram, the numeral 7 indicates the dynamo, and 8 and 9 indicate 70 the main leads with which the accumulator or battery 10 and lamps 11 are in circuit. The lamp circuit is controlled by means of a switch 12 and the main circuit is closed by an automatic cut-in-and-out switch 13 which 75 may be of any preferred automatic type which is operated to close the main circuit when the voltage of the dynamo rises to a predetermined point.

The dynamo 7 is preferably of the constant torque type and is driven from the axle of the vehicle to which the system is applied by means of a slipping belt 14, which belt is adapted to slip on the armature shaft pulley 15 when the train reaches a predetermined rate of speed. The moment of belt slippage is determined by the tension of the belt—which may be adjusted in any suitable manner—and the load of the dynamo, and the tension is determined by the engineer in the first instance, so as to cause the belt to slip at a predetermined rate, say, for example, 20 miles per hour. From zero rate up to 20 miles per hour, the armature shaft will rotate at a speed in direct ratio with 80 that of the train, and when the rate of 20 miles per hour is attained, the belt will slip and the armature will revolve at a fixed constant number of revolutions for a given load, regardless of the speed of the train. 85

It will be seen, therefore, that the generator is a constant wattage machine and we

will assume, for example, that the tension of the belt is such that the dynamo will generate 30 amperes at 30 volts or 900 watts at a predetermined rate of train speed, which we have assumed for the purposes of this specification to be 20 miles per hour. Owing to certain operative phenomena which those skilled in the art will understand, the wattage of a dynamo of this type 10 will not vary quantitatively from the predetermined standard adopted, although the voltage and amperage may and do vary inversely with respect to each other, as will further appear.

15 The dynamo is also so arranged that at a predetermined rate of train speed, say for example, 15 miles per hour, it will generate a voltage sufficient to operate the automatic cut-in switch 13 so as to close the working 20 circuit. The rate of speed of the armature at this train speed will hereinafter be termed the cut-in speed of the dynamo.

In contradistinction to the constant current and constant voltage systems which have been 25 heretofore referred to, the system employing a constant torque dynamo, when used in uniform service, does not require any means for automatically regulating either the current or the voltage so as to maintain 30 the proper rates of battery charge, because as the voltage in the battery circuit rises, during the process of charging, the amperage will be correspondingly cut down, which will result in an automatically tapering battery 35 charge, which secures a proper charging of the battery while at the same time the injurious results of over-charging are avoided. Where, however, the service is not uniform, as for example, where a car is used 40 one day on short runs during which the average rate of sustained train speeds is comparatively low, while on the next day it is used on a long run, during which the average speed attained may be higher and 45 the points of stoppage less frequent, it is advisable to adjust the system to meet the changed service conditions in order to secure the most efficient results. This will be seen from the fact that in the first class of 50 service mentioned, the battery would have to be charged at a higher rate, owing to the periods of time available for this purpose, and to meet this condition, the tension of the belt, for example, would be increased, so 55 that the dynamo would generate a greater output before the belt would slip. If a car adjusted for this class of service were used, however, on a long run, in which higher rates of speed are attained, this increased 60 output would not be necessary. It is one of the objects of my invention, as previously set forth, to make my improved system of electrical distribution adaptable to such varying classes of service as have just been 65 described without necessitating manual ad-

justment of the apparatus. I may accomplish this in several ways but I prefer the following method:

The shunt field of the dynamo which I have diagrammatically indicated at *d* is normally in circuit across the mains through the switch 76 which is normally gravity held in closed position, short circuiting an adjustable resistance 116, the purpose of which will be set forth. The switch 76 is operated 70 by an electro-magnetic device, preferably of the solenoid type, the core 75 of which is sucked up by the action of the coil 74. The switch 12, when moved to one position, puts the lamps 11 in circuit and breaks the 80 circuit in which the coil 74 of the electro-magnetic device is located, and when moved to another position, breaks the lamp circuit and closes the circuit of the coil 74. The purpose of the apparatus just described is 85 to prevent overcharging of the battery, as will be clear from the following description of the operation.

As the battery 10 approaches a state of full charge, the voltage in the circuit rises 90 because of the counter E. M. F. of the battery, and the coil 74 is so calibrated that it will be sufficiently energized to open the switch 76 when the battery voltage rises, for example, to 40 volts. When this voltage 95 is reached, the core 75 will be sucked up, opening the switch 76 and breaking the normal circuit of the shunt field and completing such circuit through the resistance 116. The effect of inserting into the field this 100 resistance 116—which may be of any pre-determined character—is to weaken the field and thereby change the load of the dynamo, with the result that the belt will not slip on the pulley 15 until the speed of the armature is greatly increased. In other words, the moment of the belt slippage is greatly retarded and the train must attain a relatively much higher rate of speed before the dynamo will generate a voltage sufficient 110 to close or to hold closed the automatic cut-in switch 13. Stated differently, the effect of the introduction of the resistance 116 into the main field is to raise or step up the cut-in speed of the generator; that is, 115 the speed at which the generator will produce useful voltage is greatly increased.

By this action of what may be termed the limiting device, the battery is fully protected against overcharge because as the 120 battery reaches a full state of charge and its voltage consequently rises, the limiting device is actuated by the rise in voltage in such way as to practically cut off the flow of charging current to the battery during 125 normal train speeds. In fact, I prefer to so arrange the resistance 116 that the generator will be unable to deliver current to the battery until the train has reached a speed of approximately 40 miles per hour, 130

and will only be able to deliver an appreciable charging current at higher rates of speed, the amount of resistance being determined so as to make it impossible for the dynamo to generate an injurious charging current until a rate of train speed is attained which is at present impossible in railway service. It will be understood, of course, that when the voltage drops to a predetermined point, the core 75 will be released and the switch 76 will be gravity closed, thus short-circuiting the resistance 116 and reestablishing normal field conditions.

15 From the foregoing it will be seen that by my improved method and apparatus, I change the moment of belt slippage by altering one of the factors by means of which said moment of belt slippage is determined 20 by an automatic means actuated upon a change in the state of the battery charge. In the preferred method which I have described hereinbefore, the factor which is thus altered is the field strength of the 25 dynamo; but it will be understood that other factors which determine the moment of belt slippage may be thus altered.

It will also be seen that by my improved method I alter the cut-in speed at which 30 the dynamo will deliver a useful current to the consuming circuit, with the result that the various advantages and beneficial results hereinbefore pointed out are obtained.

It will also be noted that the system is 35 very simple and very efficient in operation and that many of the disadvantages which are incident to the systems requiring automatic regulating devices are obviated.

I claim:

40 1. In a car lighting system the combination of a dynamo having a predetermined cut-in speed standard at which it will generate a useful current, an accumulator to be charged thereby, and automatic means actuated by change in the voltage for altering

one of the components producing said standard and thereby setting a new standard of cut-in speed at which the dynamo will deliver a useful current.

2. In a car lighting system, the combination of a slipping belt dynamo having a predetermined cut-in speed standard at which it will generate a useful current, an accumulator to be charged thereby, and automatic means actuated by change in the 55 voltage for altering one of the components producing said standard and thereby setting a new standard of cut-in speed at which the dynamo will deliver a useful current.

3. In a car lighting system, the combination of a dynamo having a predetermined constant torque, an accumulator to be charged thereby, and means automatically actuated by change in the difference of potential for altering one of the components 60 producing said constant torque thereby automatically changing the cut-in speed at which the dynamo will deliver a useful current.

4. In a car lighting system, the combination of a dynamo, an accumulator, an automatic cut-in switch automatically closed on a predetermined dynamo voltage, the said dynamo having a predetermined cut-in speed standard at which such voltage is generated, and automatic means actuated by 75 change in accumulator voltage for altering one of the components producing said cut-in speed standard, thereby setting up a new standard of cut-in speed at which the dynamo will deliver a useful current.

5. In a car lighting system the combination of a slipping belt dynamo, an accumulator to be charged thereby, and means automatically actuated upon a change in accumulator voltage for altering one of the 85 factors determining the moment of belt slippage.

In testimony whereof I have hereunto signed my name and affixed my seal.

ALFRED HENRY DARKER. [L. S.]
